UNITED STATES PATENT OFFICE.

WILLIAM PRINCE-SMITH AND DAVID WATERHOUSE, OF KEIGHLEY, ENGLAND.

FLYER BEARING.

Application filed March 9, 1925. Serial No. 14,230.

To all whom it may concern:

Be it known that WILLIAM PRINCE-SMITH and DAVID WATERHOUSE, both subjects of the King of Great Britain, residing at Keighley, in the county of York, England, have invented certain new and useful Improvements in Flyer Bearings, of which the following is a specification.

This invention relates to worsted drawing frames and analogous machines and the invention has for its object to prevent the accidental displacement of spindles and consequential damage to flyers, as occurs sometimes in practice when the slubbing breaks and the break remains undetected for a time while the machine is running, with the result that the broken slubbing becomes wrapped round the spindle and lifts the upper bearing gradually out of the supporting bracket.

According to the invention an upper support for each spindle of a worsted drawing frame or analogous machine is provided with a positively operating locking device which engages the upper bearing of the spindle to prevent the spindle from rising out of its working position and which is adapted to be rendered non-effective when it is desired to doff.

In one constructional form of the invention the collar usually supporting the spindle at its upper end is formed with an annular groove, and transversely of the supporting bracket there is arranged a movable member such as a latch or pin adapted normally to lie in the aforesaid annular groove so as to obstruct upward movement of the collar and to be released from said collar, when necessary, so as to permit freedom of movement of the collar for the purpose of detaching the spindle from the supporting bracket as when doffing.

The said latch or pin may be maintained by gravity normally in the operative position, and means may be provided which serve to indicate the "free" position of the parts when the latch or pin is actuated.

The invention is illustrated by way of example in the accompanying drawings, in which the mounting of a single spindle is shewn. Figure 1 is a side elevation, partly in section, and Figure 2 is a front elevation.

A is the spindle on which is fitted the flyer B as usual, and C is the neck of the spindle 55 which rotates in a stationary sleeve D of

which the diameter of the upper portion D' is greater than that of the lower portion, with the result that at about midway of its length the sleeve D presents a shoulder D².

The sleeve D is received between the jaws E, E, formed by the bifurcated forward end of a bracket F suitably secured to a fixed rail G, said jaws E, E, being separated sufficiently to just permit of the passage therebetween of the lower part of the sleeve D which is of smaller diameter and having a recess in their upper face of a diameter sufficient to accommodate the upper part D' of the sleeve D which is of larger diameter. The jaws E, E form a seating for the shoulder D² and thus support the sleeve D vertically. The spindle A is supported vertically at its lower end (by means not shown) in the operative or spinning position. The sleeve D may be pinned or otherwise suitably secured against rotation in the jaws E, E.

The upper part D' of the sleeve D, which is of larger diameter, is formed with a circumferential groove D³, and through a passage bored transversely through the rear upper part of each of the jaws E, E, there is passed loosely a latch or pin H which is substantially cylindrical in cross-section and adapted to fit within the aforesaid circumferential groove D³. J is a weighted handle attached to or formed on the latch or pin H and suitable means (in the present instance shown as a cotter-pin K extending through a transverse opening in the pin H) is provided for securing the latch or pin H against longitudinal displacement.

The latch or pin H, approximately midway of its length, is formed with a flat H' of such depth and length that when the latch or pin H is rotated to present the flat H' opposite to the groove D³, the obstruction offered to the vertical displacement of the sleeve D between the jaws E, E by engagement of the pin H in the circumferential groove D³ is removed.

L, M, are limiting stops formed on or carried by the handle J and the bracket F, respectively, and which serve to indicate the exact angular position of the latch or pin H in which the flat H' is in a vertical position and the rounded portion of the pin H is disengaged from the groove D³ of the sleeve or collar D'.

Normally the weighted handle or lever J

- serves to keep the latch or pin H in engagement with the groove D³. Therefore during the spinning or drawing operation the sleeve or collar D is prevented positively from being displaced vertically and consequently cannot rise up out of the bracket and thus cause the spindle to lose its upper support, even though the slubbing may break and become wrapped round the spindle.
- 10 When, however, it is desired to doff the spindle it is merely necessary to move the handle J until the stops L and M are in contact whereupon the flat H' of the pin H is brought opposite to the groove D³ and the sleeve or collar D may be moved upwardly until the wider part D' is clear of the upper ends of the jaws E, E, after which the collar D can be withdrawn from the drawing-box by being passed forwardly through 20 the space between said jaws E, E.

The above described construction is illustrative of one typical example and the design, but it is to be understood that the construction and operation of the parts may 25 be varied without departing from the spirit of the invention.

What we claim is:—

1. An upper support for spindles of 30 worsted drawing frames and analogous machines, comprising an upper bearing for a spindle, a support having partially embracing means in which the said bearing is mounted, and adjustable means carried by said partially embracing means normally 35 engaging the said bearing and operable to

be disengaged from the bearing when it is desired to effect a doffing operation.

2. In worsted drawing frames and analogous machines, a bracket, a spindle bearing supported by said bracket and having two 40 external diameters, that part of said bearing which has the larger diameter having a peripheral groove, and a latch extending substantially at a right angle to the axis of said bearing and normally engaging said annular groove, said pin being movable at will out of engagement with said groove.

3. In a worsted drawing frame or the like, a spindle, an upper bearing for said spindle having at its upper portion a collar of 50 larger external diameter than its remaining portion, a support for said bearing comprising a pair of jaws spaced from one another a distance approximately equivalent to the external diameter of the lower portion of 55 said bearing to permit said lower portion to pass therebetween and also having a recess in their upper portion to receive said collar, and a latch associated with said jaws and shiftable into and out of engagement 60 with said collar.

4. Apparatus according to claim 3 embodying means normally maintaining the latch in engagement with the collar and manually operative to release said latch.

In testimony whereof we affix our signatures.

WILLIAM PRINCE-SMITH.
DAVID WATERHOUSE.
